Specification for Design.

Patented Sept. 16, 1919.

Application filed April 9, 1917. Serial No. 160,902. Term of patent 14 years.

To all whom it may concern:

Be it known that I, ARTHUR ATWATER KENT, a citizen of the United States, residing at Rosemont, in Montgomery county and State of Pennsylvania, have invented a new, original, and ornamental Design for Spring Contact-Arms, of which the following is a specification, reference being had to the accompanying drawing, forming a part thereof.

Figure 1 is a side elevational view of a spring contact arm showing my new design therefor; Fig. 2 is a top plan view of the same; and Fig. 3 is a bottom view of the same.

I claim:

The ornamental design for a spring contact arm, as shown.

ARTHUR ATWATER KENT.
